UNITED STATES PATENT OFFICE.

PAUL J. KALMAN, OF ST. PAUL, MINNESOTA.

REINFORCING-BAR.

1,278,079.

Specification of Letters Patent.

Patented Sept. 3, 1918.

Continuation of application Serial No. 185,418, filed August 10, 1917. This application filed May 13, 1918.
Serial No. 234,143.

To all whom it may concern:

Be it known that I, PAUL J. KALMAN, a citizen of the United States, and resident of St. Paul, in the county of Ramsey and State of Minnesota, have invented certain new and useful Improvements in Reinforcing-Bars, of which the following is a specification.

This application relates to reinforcing bars for concrete and is a continuation of my co-pending application Serial No. 185,418, filed August 10, 1917.

It is desirable that reinforcing bars, whether round or rectangular in cross section, shall be provided with directly transverse ribs. Attempts have been made heretofore to roll a bar having such ribs but in no instance has it been found possible to form the ribs without distortion of some portion thereof. This in itself is objectionable in that it reduces the bonding capacity of the bar, but an objection equally great is that distortion of the ribs implies unnecessary wear and rapid deterioration of the rolls and the consumption of more power in the rolling operation than would be necessary if the bar were correctly designed.

To that end therefore I have designed a bar which may be rolled without distorting the ribs, with consequent advantages. It will be understood that reinforcing members such as commonly used today are formed by passing a heated bar between a pair of rolls, one-half of the pass being contained in each roll. The bar which is fed into the rolls is of anywhere from 25 to 35% larger cross sectional area than that of the bar which issues from the pass. This is necessary in order that there will be sufficient material to fill the grooves in the roll and form the ribs on the bar. It will be understood also that the grooves which serve to form the ribs on the bar must be arranged radially of the roll and consequently that the grooves are in line with the ribs formed on the bar only at one point; that is, at a point coincident with a line intersecting the axes of the two rolls; furthermore that the angularity between the grooves and the rib formed thereby increases with the angularity of the roll due to the tangential movement of the bar. The difficulties arising from this fact are increased due to the fact that the reduction in size of the bar implies and necessitates a corresponding elongation of the bar; that is, theoretically if there is a 25% reduction on the bar in the rolls, the bar should issue from the rolls 55 25% faster than it enters. It has been found that the elongation of the formed bar as it emerges from the roll is proportional to the amount of reduction, and is approximately 4 to 5% in excess of the speed of the periphery of the rolls at approximately 60 30% reduction. The reduction necessary depends on the width and depth of the ribs, and the lead of the bar over the peripheral speed of the rolls depends on the amount 65 of reduction. The effect of the increasing angularity between the groove in the roll 70 and the rib on the bar and the increase in speed of travel of the rib over the peripheral speed of the roll results in wiping off or distorting the portion of the rib which is not yet freed from the roll. A rib constructed as described herein will not be distorted and will be freed from the roll without conflict therewith.

I have found that by designing the bar with a rib disposed transversely thereof, one 80 face or wall of the rib may be substantially vertical and this is an important advantage due to the increased bonding capacity. I have found also that by inclining the opposite face of the rib in a certain manner with 85 relation to the height of the rib, the liability to distortion is eliminated. The proper angle is approximately 45° to the longitudinal axis of the bar, the angle varying somewhat with the height of the rib. 90 At any rate the base of the triangle formed by the inclined portion of the rib should be at least as great if not greater than the height of the rib.

The invention will be more readily understood by reference to the accompanying drawings, wherein;

Figure 1 is a transverse section through a pair of rolls showing a reinforcing bar in the process of formation in the pass;

Fig. 2 is a sectional view on the line 2-2 of Fig. 1;

Fig. 3 is a fragmentary sectional view on the line 3-3 of Fig. 1;

Figs. 4, 5, 6 and 7 are plan views showing the groove in the roll in its relative position to the rib on the bar at different points in the progress of the bar, and,

5 Figs. 8, 9, 10 and 11 are sectional views through the roll and bar, taken in the position of the parts in Figs. 4 to 7 inclusive, the views being on the lines 8—8, 9—9, 10—10 and 11—11 respectively of Figs. 4

10 to 7.

The bar is shown as being generally rectangular in outline although it may be made round if desired. It is preferably provided with a main or body portion 10, having 15 four diametrically opposed longitudinally extending corner ribs 11. The longitudinal ribs are joined by directly transverse ribs 12, one face 13, of which is substantially perpendicular to the longitudinal axis of 20 the bar while the other face 14, is inclined at an angle substantially 45° to the said axis of the bar.

In order to produce a bar such as described it is received in the pass formed by 25 peripherally grooving two rolls 15, 16, one half of the pass being formed in each roll. The peripheral grooves of the roll are transversely grooved as at 17, in order to properly shape the rib on the bar. It has been

30 found in practice that due to the elongation of the bar, the distance between adjacent ribs 12, on the bar is greater by 4 to 5% than the distance between adjacent grooves 17, on the roll and this, when taken in connection with the peculiar angular relation of the parts due to the tangential movement of the bar, causes the portions 18, of the rib (best shown in Fig. 3) to be wiped off or distorted, the distortion being greatest at 40 the point indicated and being lessened to a point extending to nearly the end of the rib. I have discovered that by designing the rib as described herein its distortion may be avoided. The reason for such design is

45 illustrated in Figs. 3 to 11 inclusive. In these figures it will be seen that the groove 17, in the roll immediately on leaving the central position at which the rib is formed begins to move angularly away from the

50 formed rib, but as the longitudinal axis of the groove is always radial to the roll and as the longitudinal axis of the formed rib is always perpendicular to the longitudinal axis of the tangentially moving bar, the

55 tendency is for the rib to be caught in the groove, particularly when it is borne in mind that the speed of travel of the bar is increased over the peripheral speed of the roll. In Fig. 11 I have indicated in dotted

60 lines a triangle whose hypotenuse 19, is the incline on the rib and whose altitude 20, is the height of the rib. The length of the base 21, therefore controls the angle 19, and in the appended claims the base 21, of the tri-

angle thus formed is indicated as being of 65 greater length than the height of the rib. This implies that the angle 19, shall be less than 45°. This angle may be lessened if desired, but the figures illustrate that this is approximately the extreme angle which may 70 be employed for rolling a rib without distortion. The dot and dash lines indicate an intermediate position in Fig. 1, and are shown for the purpose of illustrating, as in Fig. 3, the manner in which the groove is 75 in effect twisted with relation to the formed rib.

The bar herein illustrated possesses material advantages in that it may be formed as shown. Other bars have been illustrated and described having ribs which may form an equally efficient bond but such ribs cannot be rolled and the reason therefor will be apparent from the foregoing description. The vertical face of the rib provides an extremely efficient abutment for the cementitious material.

It will be understood, of course, that the ideas here expressed and the difficulties encountered in rolling the bar are the same 90 whether the bar is rectangular or round or intermediate of shapes.

I claim:

1. A reinforcing member for concrete comprising a bar having spaced directly 95 transverse ribs thereon one face of each rib being substantially perpendicular to the longitudinal axis of the bar and the other face of each rib being inclined substantially 45°, substantially as described.

2. A reinforcing member for concrete comprising a bar having spaced transverse ribs thereon, one face of the ribs being substantially perpendicular to the longitudinal axis of the bar and the other face being inclined, the incline constituting the hypotenuse of a triangle whose base has a length at least as great as the height of the rib, substantially as described.

3. A rolled deformed bar having a transverse rib provided with a face at substantially right angles to the longitudinal axis of the bar, the opposite face of the rib being materially inclined outwardly toward the first mentioned face to give clearance in the 115 forming rolls.

4. A rolled deformed bar having a body portion provided with a plurality of continuous transverse ribs surrounding the bar, one face of each of the transverse ribs being 120 substantially perpendicular to the longitudinal axis of the bar, the opposite face of each of the said ribs being materially inclined outwardly toward the first mentioned face of the rib.

5. A reinforcing member for concrete, comprising a bar having a body portion provided with a plurality of spaced transverse

ribs substantially surrounding the bar, one face of each of the transverse ribs being substantially perpendicular to the longitudinal axis of the bar, and the opposite face of each of said ribs being materially inclined from the base thereof outwardly toward the first mentioned face of the rib, and connecting

with said first mentioned face of the rib by a flat part.

Signed at St. Paul, Minnesota, this 10th ¹⁰ day of May, 1918.

PAUL J. KALMAN.
